UNITED STATES PATENT OFFICE.

ALFRED THEODORE HESPE, OF WEEHAWKEN, NEW JERSEY.

ADJUSTABLE-CONTACT THERMOMETER.

1,207,754.

Specification of Letters Patent. Patented Dec. 12, 1916.

Application filed September 2, 1914. Serial No. 859,836.

To all whom it may concern:

Be it known that I, ALFRED THEODORE HESPE, a citizen of the United States, and a resident of the city of Weehawken, county 5 of Hudson, and State of New Jersey, have invented certain new and useful Improvements in Adjustable-Contact Thermometers, of which the following is a specification.

The object of my invention is to provide 10 a thermometer so arranged and constructed that a part thereof may be adjusted over the entire scale and in such a manner that when the mercury advances to a predetermined point an electrical circuit will be established or broken. In the past thermometers have been constructed to accomplish 15 this useful purpose but such thermometers have been difficult of construction and have been inefficient in that the point of contact 20 cannot be changed at the will of the operator. Such devices are usually constructed by inserting into the mercury tube or reservoir a single wire, and at other predetermined points upon the staff or upright tube 25 of the thermometer one or more additional wires were molded into the glass. It will be readily seen that thermometers so constructed are not capable of adjustment and cannot indicate the movement of the mercury at any 30 point other than those wherein a wire projects into the tube.

In my device I have arranged so that the point of contact may be adjusted even to a fraction of a degree and may be changed entirely at the will of the operator.

The construction of my device and its method of operation will be fully set forth as the specification progresses.

The following is what I consider the best 40 means of carrying out my invention, and the accompanying drawing forms part of this specification, in which:

Figure 1 shows a front elevation of my thermometer. Fig. 2 shows a part on a 45 larger scale and is partly in section. Fig. 3 shows in section and elevation a modified form.

Similar reference numerals indicate like parts in all the figures where they appear.

At 1 I have shown the board or mount of 50 a thermometer and upon it will be found the ordinary scale 2 subdivided in any well known manner. At 3 I show the tube or staff of the thermometer. At 4 the bulb or mercury reservoir, and at 5 and 6 bell and battery. All these parts with possibly the

exception of the tube or staff 3 are of ordinary construction, and therefore require no lengthy description as to their functions as they are well understood.

Adjacent to the upper end of the tube or staff 3 I provide a bulb or reservoir 7 by slightly increasing either the interior or exterior diameter of the tube 3. This reservoir 7 is integral with the tube 3, and must connect with the interior passage of the tube 3. Into this reservoir I place a solution of creosote, and as the upper end of the reservoir 7 is opened the creosote will exclude air and moisture from the passage through the 70 tube 3.

Into the mercury in the bulb 4 I insert a wire, preferably a copper wire tipped with platinum, the platinum tip being molded into the glass and projecting into the mercury in the reservoir. This wire may be attached to a suitable binding post 8, and a second wire from the binding post 9 will be secured to a metal thimble 10 into which the upper end of the reservoir 7 is secured.

Screw threaded or otherwise connected with the thimble 10 is a metallic box 11 containing a spool 12, upon which a length of wire, preferably platinum wire 13, is wound. One end of the wire is secured to the spool, 85 and the other end is inserted through the thimble 10 and reservoir 7, and through the creosote solution into the tube 3. The key 14, is provided for winding the wire around or unwinding the wire from the spool 12, 90 and I also provide a stationary guide roller 15, and a movable guide roller 16, to insure that the wire 13 will receive sufficient friction to produce satisfactory electrical contact. It will be seen then that the guides 95 through which the wire passes are to be of metal.

The bell 5 and the battery 6 are connected with the binding posts 8 and 9 in a well known manner by means of any ordinary 100 wires 17 and 18, and now when the wire 13 is inserted to a predetermined point within the tube 3, and the mercury advances to that point, a complete electrical circuit through the thermometer and through the battery 105 and bell will be established and a signal given, and it will be readily understood that the adjustment of the wire 13 in the tube 3 may be accomplished by merely turning the key 14, either to advance the wire into the 110 tube or to withdraw it therefrom.

It is necessary to maintain a close elec-

trical contact between the thimble 10 and the wire 13. I have therefore made the box 11 of metal and the spool 12 is also of metal. Upon leaving the spool the wire passes over 5 the roller 15 and the roller 16 which is free to operate in the slots 16' in which it finds bearing will contact with the wire 13, and with sufficient force to insure electrical contact between the parts.

10 I have found that it is possible to construct my device in a somewhat different manner and this construction is shown in the modification Fig. 3. Here the tube 3 is provided with an enlarged portion which 15 produces the chamber 7' into which a creosote solution is placed. The rod or wire 20 passes into the mercury tube 3, and its outer end is secured to a cap 21. The inner end of the wire 20 projects to a considerable distance below the lower end of the cap 21 so that when the cap 21 is moved over the scale or over the tube 3 the lower end of the wire 20 may be readily observed and will not be limited in its operation by the cap 21. A 25 soft packing ring 22 is arranged at the lower end of the cap 21, and bears upon the outer surface of the tube 3. The cap 21 is held in fair bearing upon the tube 3 by the exterior of the chamber 7' and the interior of the 30 packing ring 22. I may guide the movement of the cap 21.

It will be understood that further modifications may be made within the scope of the appended claims without departing from the principle or sacrificing the advantage 35 of this invention.

I have found that my thermometer may be used in a great number of ways and although I have shown it operated with a battery and alarm, I desire it understood that it 40 may, when connected with suitable relays, or other electrical device be used to start or stop machinery, open or close valves, or doors, or perform any other duties that may be imposed upon it provided that they are 45 within the scope of the possibilities of the device, and that the current caused to pass through the mercury and movable metallic

member is not sufficient to fuse or vaporize either.

Having carefully and fully described my invention, what I claim and desire to secure by Letters Patent is:

1. A thermometer having a mercury tube, 55 mercury therein, a flexible metallic member entering said tube, a rotatable spool upon which said flexible member is adapted to be wound to adjust said flexible member within said tube and an electric circuit adapted to be closed through said mercury and said 60 flexible member.

2. A thermometer having a mercury tube, mercury therein, a casing supported by said tube, and electric circuit one side of which is connected to said casing and the other end 65 of which enters the said mercury, a metallic member entering said mercury and adapted to be rolled within said casing and means between said roll and said mercury for electrically engaging said metallic member with- 70 in said casing.

3. An adjustable thermometer having a mercury tube and chamber formed integral, mercury within said tube and said chamber, a second chamber formed in said tube, a 75 non-corrosive, non-conductive liquid therein, a metallic thimble and casing supported by said tube, and a flexible metallic member operative through said casing, said thimble and said second chamber, and into said mer- 80 cury tube, a rotatable spool in said casing upon which said flexible member is adapted to be wound, and a plurality of rollers, one of which is adjustably supported by said casing and adapted to receive said flexible 85 member between them to guide said flexible member and continue an electrical contact between said casing and said flexible member.

Signed at New York city, N. Y., this 13th day of August 1914 A. D. in the presence of 90 these two witnesses.

ALFRED THEODORE HESPE.
